UNITED STATES PATENT OFFICE.

ANDERS JORDAHL, OF NEW YORK, N. Y.

AIR FILTER.

Application filed May 10, 1924. Serial No. 712,280.

To all whom it may concern:

Be it known that I, ANDERS JORDAHL, a subject of the King of Norway, residing at New York, in the county and State of New York, have invented certain new and useful Improvements in Air Filters, of which the following is a specification.

The present invention relates to air and gas filters of the type employing a fibrous material as a filter medium, such medium being metal wool; shavings of steel, monel, aluminum, copper or brass, etc.; or it may be asbestos or other natural or artificial mineral wool, or animal or vegetable fibre. Such materials have heretofore been packed into the filter cells in a loose and free state which of course sets up many disadvantages, some of which may be mentioned as follows. It is a difficult matter to pack the fibre in a comparatively large area, such as a filter cell which is generally 18" by 18", in order to obtain a layer of uniform density and furthermore difficulties arise when such a layer of fibre is to be washed, after it has become dirty, without taking it out of the filter cell and if it is taken out, it is difficult to replace it. Also in placing a layer of fibre between two large screens or perforated plates it has a tendency to bulge out in the center portion, thus making it non-uniform both in thickness and density and furthermore this layer of fibre has a tendency to settle whereby the lower strata are compressed but the upper strata are porous of which the top may even be empty. It is also a fact that almost any kind of fibre arranged in a layer of large area will lose its uniformity of structure in the course of a washing process as some of it will disintegrate and be carried away with the washing liquid and some of it will form into "tufts" of a greater density, all of which will give it a spotted appearance when held against a light. It is also necessary to renew the fibre from time to time and this can only be successfully accomplished by experienced men.

The above objections are overcome by forming the fibrous material of the filter cell into a plurality of small mats each of which is enclosed in a casing of fine mesh wire netting or in thin perforated sheets, or fine mesh expanded metal and the like. These mats are preferably made thin and narrow but of a length equal to the width of the filter cell. A further object of this invention is to so construct the cell in order that

the mats may be removed for individual washing which enables a much more thorough cleaning and this object is attained by means of removable bars. A still further object of this invention is to construct each mat to contain two or more layers of filter media of varying coarseness and consequently of varying density. Further objects will be apparent from the following specification taken in connection with the accompanying drawing in which like reference characters indicate corresponding parts throughout, and in which:

Figure 1 is a front view of the filter unit, 70

Fig. 2 is a section of the unit taken on line 1-1 of Fig. 1,

Fig. 3 is a detail of a part of the mat on an enlarged scale and partly broken away,

Fig. 4 is a section of a part of the unit 75 showing another form of a mat, and

Fig. 5 is a detail of a part of the mat of Fig. 4 on an enlarged scale and partly broken away.

This filter apparatus is built in the form 80 of units and since this invention resides in the specific construction of the unit the specification and drawing have been limited to a single filter unit. This unit comprises a frame 1 having flanges 2 and 3 bent at 85 right angles but in opposite directions to the web portion 4. In this frame a perforated plate 5 is provided which is adapted to be inserted against the flange 2 and this plate is provided with suitable perforations 90 6. This plate is shown only by way of example since a screen or other suitable means could be employed. The frame is adapted to receive a plurality of slat-like filter mats 7 which are secured in the frame by the 95 plate 5 on one side and by the bars 8 on the other or outer side. These bars are secured in the frame in any suitable manner, such as for instance inserting them through suitable holes in frame 1 through 100 which the ends 9 project, but of course a screen could be used in place of these bars. These mats 7 comprise a casing 10 of a suitable wire netting which encloses the filter medium 11. Any suitable method can be 105 employed in making these mats such as wrapping the netting around the filter medium and then soldering it together to be then pressed into the desired shape or the casing can first be made after which the 110 filter medium can be pressed therein. It is

of course understood that the word "mat"

2
may include any filter material as outlined in the opening paragraph.

Figs. 4 and 5 show another form of filter mat which is also enclosed in a wire casing 10 but which is provided with a plurality of layers of filter media of varying coarseness. Layer 12 is the coarse layer, 13 the medium, and 14 the fine layer, the object being that the coarse layer is placed toward the dirty air or the outside and the fine layer on the inside as shown in Fig. 4, the arrows representing the direction of the air current through the filter cell. While the mats are shown as arranged on their sides in Fig. 4 instead of on their ends as in Figs. 1 and 2 it is however understood that they can be arranged in any suitable manner and each mat can be made in any desired shape and thickness whereby also the number of mats 20 for each unit can be varied depending upon the service required. Layers 12, 13 and 14 can also be varied in number and each layer may be provided with a casing of wire netting, not shown, thus allowing the individual layers to be removed from the casing 25 by a suitable opening, not shown, at the end.

The chief advantages produced by this invention resides in the production of a layer of fibrous material of uniform thickness and of a uniform density which prevents settlement of the fibrous material. Furthermore the individual mats can be removed from the filter frame for washing purposes and since the filter medium is 30 packed into comparatively small mats none of the material can wash away. These mats being interchangeable they can be easily replaced when necessary and this can be done by unskilled labor thus reducing the

cost of upkeep. It will therefore be seen 40 that by the use of a plurality of small mats into which the fibrous material is packed, new and important results are obtained which could not be obtained in filter units wherein the fibrous material is inserted in a 45 loose state.

I claim as my invention:

1. An air filter comprising a frame; a screen-like plate in said frame; a plurality of mats in said frame and against said plates; and a plurality of bars in said frame for securing said mats in place. 50

2. An air filter comprising a frame; a perforated plate secured in said frame; a plurality of wire-net casings arranged in 55 parallel relation in said frame; a filter medium in each casing; and means for removably securing said casings in said frame and against said plate.

3. An air filter comprising a frame; a 60 perforated plate in said frame; a plurality of mats in said frame and against said plate; and means for removably securing said mats in said frame, each mat having a plurality of layers of different density 65 therein.

4. An air filter comprising a frame; a perforated plate in said frame; a plurality of mats in said frame and against said plate; and a plurality of bars adapted to be 70 secured in said frame for removably securing said mats in said frame, each mat having a plurality of layers of filter media of different densities therein.

In testimony whereof I affix my signature. 75

ANDERS JORDAHL
